UNITED STATES PATENT OFFICE.

WILLIAM J. SULLIVAN, OF CHICAGO, ILLINOIS, ASSIGNOR TO THE AMERICAN EQUIPMENT COMPANY, OF CHICAGO, ILLINOIS, A CORPORATION OF OHIO.

BRICKKILN AND METHOD OF SETTING AND BURNING.

Application filed November 1, 1920. Serial No. 420,925.

To all whom it may concern:

Be it known that I, WILLIAM J. SULLIVAN, a citizen of the United States, and resident of Chicago, in the county of Cook and

5 State of Illinois, have invented an Improvement in Brickkilns and Methods of Setting and Burning, of which the following description, in connection with the accompanying drawings, is a specification, like letters

10 on the drawings representing like parts.

My present invention is a novel brick kiln preferably of the open or field kiln type and an improved method of burning the same. Important objects of the present in-

15 vention are to enable a brick kiln to be built entirely by means of mechanical setters, including the arches or lower benches; a novel construction of a kiln so built by mechanical setters; a means of setting or "pulling" the

20 brick to form the arches; and an improved construction which will simplify the labor involved in kiln and arch building, save time in burning, and will enable the brick in the arch to be utilized as serviceable,

25 marketable brick, thus increasing the percentage of good brick in each kiln.

Heretofore it has been customary, in building brick kilns, to construct the lower benches or arches with the legs for each arch

30 of four rows of brick lengthwise for the thickness of the arch. Also the space for the arches has been usually equal to two brick lengths in width of arch. This prior

35 construction required considerable manual labor, both in the setting of the brick for the legs of the arch, and in pulling the brick over the arch space to form the top, all of which had to be performed by hand, and involved labor, time and expense. With such

40 prior constructions, also, the heat supplied to the kiln through each arch was so intense that the brick adjacent each arch usually melted down or became so distorted that all these brick were thrown away as unmarket-

45 able. The difficulty of burning laterally through the brick in the arch legs also required intense heat and it has been presumed that this waste brick was a necessary percentage of loss in such kilns. In my

50 present invention I have eliminated this loss, as well as the labor and difficulty of forming the arches. I first provide a kiln with

substantially twice as many arches as heretofore customary. This construction enables the arches to be formed of narrower width, 55 i. e., approximately the length of one brick in width, thus providing space for twice as many applications of heat and thereby enabling the heat supplied to be of proper degree rather than of undue amount. Furthermore, by having the legs of the arches 60 relatively narrow, the brick in these legs are readily burned, and as the heat supplied in each arch is not excessive, these brick in each of the arch legs are burned to a proper and 65 marketable temperature.

A still further important advantage resulting from my invention, is that a kiln with these relatively narrow arches can be built by a mechanical setter, the setter pref- 70 erably being adapted to carry two arch legs.

It is customary at present in the brick art utilizing mechanical setters, when building kilns, to load the setter with a brick unit of four brick in length. Consequently by un- 75

loading one half the setter unit, i. e., two brick in length, to form the leg of an arch, spacing the remaining one half the desired 80 distance, preferably the length of a brick, and then setting the second half of the unit,

the entire lower arch bench of the kiln can be quickly built by a setter. This construction also presents to each arch one of the 85 brick, lengthwise therein, which are in the lowermost rows, the remaining brick—with

the usual setting of three over one—being sufficiently above to receive and absorb the 90 burning heat and to be burned into marketable brick. An additional advantage consists in the ease and facility of closing the arches at their top when thus formed narrow.

A single row of brick can be readily pulled out from each side approximately a quarter of the distance, and the next unit of brick set on top of the same. Heretofore in 95 closing arches of the usual width, it was necessary and customary to pull a plurality of rows of brick, usually four rows being required to close the arch at its top, all necessitating hand operation, disrupting the unit 100 formation, and as these arch brick were usually overburned, increasing the percentage of loss in each kiln.

My present invention is preferably adapt-

ed for burning with gas or oil, and greatly conserves the heat in this method of burning because of the narrow walls of the arch. By having a larger number of arches and 5 burners, the kiln can be more quickly brought up to the desired temperature and then the supply of heat reduced in each arch to prevent overburning and yet to complete the burning of the kiln more rapidly than 10 by any other method. The legs of the kiln are quickly burned, being only one brick lengthwise in depth, practically no waste brick will result, and substantially one hundred percent burned perfect brick is produced. The kiln cannot only be set 15 economically and quickly by mechanical setters, but may also be unloaded, and thus eliminate hand work almost entirely.

I believe that my improved construction 20 of a brick kiln with narrow arches, capable of being closed with a single course at the top, suitable to provide arch legs of narrow width, resulting in a completely burned and not overburned mass of brick in the lower 25 benches, as well as throughout the stack, and a construction giving greater flexibility in the heat supply and control through a greater plurality of arches, while permitting complete building and unloading by mechanical setters, is a distinct novelty, and 30 I wish to claim these features broadly.

Referring to the drawings illustrating my invention in preferred embodiment,

Fig. 1 is a fragmentary view of a portion 35 of my improved kiln construction.

Fig. 2 is a diagrammatic view illustrating the building of my kiln by mechanical setters.

As shown in Fig. 1, the kiln is built with 40 brick hacked in the usual manner of three over one, and the arches, 1, 3, 5, 7, etc., are formed by spacing the legs designated generally at 2, 4, 6, 8, etc., a distance approximately equal to the length of one brick. 45 These legs, 2, 4, 6, etc., are preferably one half the setting length employed in building the kiln, thus facilitating the handling of brick by a mechanical setter without interrupting the continuity of the units employed. As illustrated in the second unit 50 row, the full units are there set and are indicated at 15, 16, 17, etc., these being set in regular order and without interruption on the half units forming the legs. By reason 55 of the narrow arch spaces, 1, 3, 5, etc., I am enabled to close the top of these arches by pulling out a single course of brick, spacing the topmost row of the arch legs, which course is here shown at 20, a single brick 60 from either side being pulled inwardly to partially close the arch as shown at 21, 21, and leaving a space inside which may be filled by an additional brick 22, 23, 24, etc. With the arches thus formed, the next ad- 65 jacent unit 15, 16, 17, are set directly upon

the lowermost unit, and by reason of having the small arches closed with a single course of brick, a substantially level and uniform base on which to rest the units 15, 16, 17, 18, etc., is supplied. These advantages and features very greatly increase the facility and speed with which a kiln may be built. The small arches also save space in the kiln shed.

As shown in Fig. 2 the kiln formed with 75 the small arches 1, 3, 5, etc., is here shown being built by a mechanical setter, the latter showing a unit 30 being carried by a mechanical setter 35 of a type illustrated in R. C. Penfield Patent No. 999,519, dated 80 Aug. 1, 1911, this being a well known type. Any suitable crane can be utilized to handle such a setter, but as here illustrated a traveling crane 40 adapted to traverse tracks 85 41, 41, mounted on a framework or support 41 at either side of the kiln, carrying the transverse carriage 44, carrying hoisting drums to raise and lower the turntable 45 to which the setter 35 is attached. In building the lower benches the setter is operated to unload one-half of the unit 30 to form the course at the bench 2, for example, then spaced the desired distance—approximately the length of one brick—and the remaining half is lowered to form the leg 4, the attendant pulling out the adjacent bricks 21, 21, to close the top of the arch and fitting in the bricks 22 and 23. This process is repeated until the entire lower bench 90 of the kiln is laid or until that part is laid 100 on which it is desired to build the upper units. Thereupon the setter unloads the upper units 15, 16 and 17 full and complete. With the kiln thus built, the firing is caused by supplying the heat preferably through 105 oil or gas burners in each arch and owing to the greater number of arches and burners thus supplied, the kiln can be quickly brought to a burning temperature without melting down, distorting or destroying the 110 face brick in each arch. Thereupon the fires can be reduced in the arches and the burning heat maintained without forcing excessively high temperatures through the adjacent brick of the arches. The legs of the 115 kiln being narrow, are readily burned to weather-proof hardness and will be as good and marketable brick as that in the rest of the kiln. When burned, the brick may be unloaded by a similar mechanical setter, 120 as the units will be substantially unimpaired.

My invention is further described and defined in the form of claims as follows:

1. That improvement in the art of burning brick which consists in building a kiln 125 with relatively narrow arches and substantially twice the number heretofore employed, supplying heat to each arch in desired amount to bring the kiln to initial temperature, then reducing the heat in each arch to 130

prevent overburning of the arch brick and maintaining said reduced heat until the burning is completed.

2. The improved method of building a brick kiln which consists in forming the arches of substantially a space of one brick length in width and of relatively great number, forming the arch legs of approxi-

mately two brick lengths in width, closing the top of each arch by pulling out the brick of a single course, and completing the building of the kiln thereon by mechanical setting means.

In testimony whereof, I have signed my name to this specification.

WILLIAM J. SULLIVAN.
